(57) **CLAIM**

The ornamental design for a car, replica, as shown and described.

DESCRIPTION

FIG. 1 is a perspective view of a car, replica in accordance with the new design.

FIG. 2 is a front view thereof.

FIG. 3 is a rear view thereof.

FIG. 4 is left side view thereof.

FIG. 5 is a right side view thereof.

FIG. 6 is a top view thereof.

FIG. 7 is a bottom view thereof; and,

FIG. 8 is another perspective view thereof.

The dash-dot broken line in FIGS. 3-5 and 7 represents a boundary line and forms no part of the claimed design. The remaining broken lines depict portions of the car and scale model thereof that form no part of the claimed design.
